Primary Examiner—Nelson C. Holtje(74) *Attorney, Agent, or Firm*—Calfee, Halter & Griswold LLP(57) **CLAIM**

The ornamental design for a manual valve actuator with cam, as shown.

DESCRIPTION

FIG. 1 is a top view of manual valve actuator with cam and mounting bracket showing the new design;

FIG. 2 is a front view of the manual valve actuator with cam and mounting bracket of FIG. 1;

FIG. 3 is a bottom view of the manual valve actuator with cam and mounting bracket of FIG. 1;

FIG. 4 is a back view of the manual valve actuator with cam and mounting bracket of FIG. 1;

FIG. 5 is a right side view of the manual valve actuator with cam and mounting bracket of FIG. 1; and,

FIG. 6 is a left side view of the manual valve actuator with cam and mounting bracket of FIG. 1.
